(57) **CLAIM**

We claim the ornamental design for a buckle for a rifle sling, as shown and described.

DESCRIPTION

FIG. 1 is a front, top perspective view of a buckle for a rifle sling according to the invention.

FIG. 2 is a rear, bottom perspective view of a buckle for a rifle sling according to the invention.

FIG. 3 is a top, plan view of a buckle for a rifle sling according to the invention.

FIG. 4 is a bottom, plan view of a buckle for a rifle sling according to the invention.

FIG. 5 is a front, elevational view of a buckle for a rifle sling according to the invention.

FIG. 6 is a rear, elevational view of a buckle for a rifle sling according to the invention.

FIG. 7 is a right side, elevational view of a buckle for a rifle sling according to the invention; and,

FIG. 8 is a left side, elevational view of a buckle for a rifle sling according to the invention.

The broken lines having equal dash lengths in the drawings illustrate structure and/or features that form no part of the claimed design. The dash-dot-dash broken lines define the bounds of the claimed design and form no part thereof.

1 Claim, 8 Drawing Sheets
